UNITED STATES PATENT OFFICE.

REES REES, OF KAPUNDA, SOUTH AUSTRALIA, AUSTRALIA.

METHOD OF AND MEANS FOR BLOCKING OR CORRUGATING HEADERS FOR STEAM BOILERS.

1,415,706.

Specification of Letters Patent.

Patented May 9, 1922.

Application filed September 2, 1921. Serial No. 498,062.

(GRANTED UNDER THE PROVISIONS OF THE ACT OF MARCH 3, 1921, 41 STAT. L., 1313.)

To all whom it may concern:

Be it known that I, REES REES, a subject of the King of Great Britain and Ireland, residing at Smedley Street, Kapunda, State 5 of South Australia, Commonwealth of Australia, have invented a certain new and useful Improved Method of and Means for Blocking or Corrugating Headers for Steam Boilers, (for which I have filed application 10 in Australia, Patent No. 15,951, dated June 9, 1920, and in New Zealand, Patent No. 44,028, dated June 24, 1920,) of which the following is a specification.

This invention relates to the blocking or 15 corrugating of previously formed plain rectangular tubes to form headers for use in the construction of steam boilers. In particular my invention relates to the use in combination with top and bottom dies of a number 20 of specially shaped blocks and an intermediate draw-bar forming as it were a core. The blocks and bar are assembled with the aid of several approximately semicircular plugs in an open-topped box and, after removal 25 of the plugs, are pushed from the box into the plain rectangular tube which has been previously heated; the tube is placed between the top and bottom dies which are then forced together giving to the tube the 30 desired corrugations, after which the bar is withdrawn and the blocks shaken out.

In order that my invention may be more clearly understood I will describe the same 35 with reference to the accompanying drawings in which.

Figs. 1 and 2 represent front and end 40 views respectively of a plain rectangular tube as prepared ready for corrugation, Fig. 3 represents diagrammatically the same tube in position between top and bottom dies with the specially shaped blocks and intermediate draw-bar in place within the tube.

Fig. 4 is a central sectional view showing 45 the top and bottom dies closed with the corrugated tube between them and with the blocks and draw-bar still in position.

Fig. 5 is an end view of the same.

Fig. 6 is a front view showing the specially 50 shaped blocks, the semicircular plugs, and the draw-bar assembled within the open-topped box prior to being pushed into the tube.

The header is first made in the form of a

plain tube A of rectangular section with open ends as shown in Figs. 1 and 2 of the 55 required size and shape, by drawing or by bending and welding or by other means as preferred.

The loose blocks B are made of the several 60 sizes and shapes shown more particularly in Figs. 4 and 5 and by dotted lines in Figs. 3 and 6 so that together they form the curves or corrugations required and so that they will readily drop out from the corrugated tube when the draw-bar C has been removed. 65 It will be noticed from Fig. 5 that there are two rows of blocks at the bottom and two rows at the top, the abutting faces of the blocks being inclined and not vertical.

The loose blocks B are assembled in an 70 open-topped box D, see Fig. 6, the approximately semicircular plugs E which run through the sides of the box assisting in holding the bottom blocks in place until the bar and the upper blocks have been placed in 75 position. When the bottom blocks B have been placed in position the bar C is laid upon them and the top blocks are then placed in position upon the bar, the blocks and bar forming as it were a core. When the blocks 80 are in true position the semicircular plugs E may be and are removed.

The tube A having been heated and placed in position upon the lower die K, the open-topped box D is placed with its one end 85 against the end of the tube A, the semicircular plugs E are withdrawn, and the core formed by the whole of the blocks B together with the bar C is pushed along by a suitable device such as a press into the 90 heated tube A, this position being indicated in Fig. 3.

Pressure is then applied to the dies H and K and the tube being passed between the external dies and the internal core it is corrugated to shape as shown in Fig. 4. The dies are operated in the usual manner by means of an hydraulic press or by means of a steam press of the usual construction. 95

The bar C is immediately withdrawn, and 100 upon the now corrugated tube or header being removed from the dies and upended the loose blocks B fall from the header ready for use in another blank.

The ends of the header are then closed by 105 welding or other means, and the header is

ready for machining to take the required tubes and connections.

What I claim is:—

1. The method of blocking or corrugating a plain rectangular tube to form a header for a steam boiler which consists in:—assembling a number of specially shaped blocks and an intermediate draw-bar with the aid of several approximately semicircular plugs 5 in an open-topped box to form as it were a core; inserting the assembled blocks and draw-bar in a heated tube, then pressing the same between top and bottom dies; and then withdrawing first the draw-bar and then the 10 blocks.
2. Means for blocking or corrugating a header for a steam boiler, comprising top and bottom dies, and a core formed of a number of suitably shaped blocks, and an 15 intermediate frictionally held draw-bar, the blocks being arranged on opposite sides of the draw-bar in two longitudinal rows on each side, the blocks of the rows on one side

being separate and independent of and spaced from the blocks of the rows on the 25 other side, the abutting faces of the blocks of the rows being inclined, whereby when the tube has been pressed to shape the draw-bar can be readily removed and the blocks shaken from the tube.

3. In the construction of a corrugated header for a steam boiler, specially shaped blocks and an intermediate draw-bar forming an internal core, and means for assembling the blocks and draw-bar, comprising 30 an open-topped box and a number of approximately semicircular plugs running through the sides of the box.

In testimony that I claim the foregoing as my invention I have signed my name in the 40 presence of two subscribing witnesses this 25th day of July 1921.

REES REES.
